UNITED STATES PATENT OFFICE.

WILLIAM HUGH ROSE, OF TORONTO, ONTARIO, CANADA, ASSIGNEE, BY MESNE ASSIGNMENTS, TO THOMAS W. SELF, OF TORONTO, CANADA.

MEANS FOR COLLECTING AND RETURNING CONDENSATION IN STEAM SYSTEMS.

Application filed September 14, 1922. Serial No. 588,273.

The objects of this invention are to devise a means for collecting and returning the condensation from a steam system to a boiler which will not be liable to get out of order and dispenses with the use of a circulating pump, being adapted for pumping of liquids against a pressure or equalizing pressures in fluid lines.

The principal feature of the invention consists in the novel arrangement of a receiving tank in a steam system and a balanced pressure control valve in the live steam line whereby the hydrostatic pressure of a column of water fed from the tank is utilized to open the steam valve and allow admission of boiler pressure to equalize the pressure in the tank with the boiler.

Another important feature consists in the novel arrangement and construction of valves with a pair of equalizing tanks whereby a continuous flow of the condensed water will be maintained.

In the drawings, Figure 1 is a diagrammatic elevation of a duplex installation.

Figure 2 is an enlarged elevational view partly in section of the valves leading to and from the tanks.

Figure 3 is a longitudinal sectional view of the valve for controlling the direction of flow of the inflowing condensation.

Figure 4 is a longitudinal sectional view of the balanced steam control valve.

In the handling of condensation in a steam plant it has been the common practice to use dump traps and circulating pumps but these devices are subject to peculiar defects that are highly undesirable and the present invention overcomes these objectionable features.

In the example shown, a duplicate set is illustrated as it is most desirable for the purpose of a continuous feed. In the structure shown, vertical tanks 1 and 2 are provided with pipe extensions 3 and 4 respectively leading from the bottom and in these

pipe extensions are arranged the Ts 6 and 7 connecting with the check valves 8 and 9. Each of these check valves is set to allow flow toward the respective tank. Gate valves 10 and 11 are provided to regulate the speed of flow and these connect with a balanced diaphragm valve 12 which is provided with an intake 13 at the bottom, which intake is connected with the steam system.

The valve member 14 controls the flow in

one direction, that is to say, by its operation it either opens or closes access to the tank 2. The valve stem 15 is operated by a diaphragm 16 and a pipe 17 connects the top of the diaphragm chamber to the tank 1 at a point adjacent to the top so that when high pressure steam enters the tank 1 it will flow into the pipe 17 and operate the diaphragm 16 to open the valve 14 to allow the condensation to flow into the tank 2.

The pipe lines from the tanks are continued beyond the Ts 6 and 7 and lead to the central boiler connection 18, check valves 19 and 20 being interposed to allow outflow from and prevent back flow to the tanks. Gate valves 21 and 22 are also provided to regulate the speed of flow.

High pressure steam pipes 23 and 24 are connected by the pipes 25 and 26 to the top of the tanks 1 and 2 respectively and air valves 27 and 28 are arranged in said connections. Balanced valves 29 and 30 are arranged in the branch steam lines leading to the tanks. These valves are provided with diaphragms 31 operating the valve spindles.

Pipes 32 and 33 connected with the tanks 1 and 2 respectively at a point adjacent to the top, extend downwardly and are connected at the bottom ends into the main flow lines from the bottom of the tanks, check valves 34 and 35 being interposed at the bottom ends.

Branch pipes 36 and 37 connect the pipes 32 and 33 with the valves 29 and 30 respectively. The valves 29 and 30 are balanced and are normally held closed by the springs 38, balancing steam pipes 39 being arranged to connect with the underside of the diaphragm. These pipes have the gauges 40 arranged therein.

Any pressure present in the tank flows in the pipes 25 and 32 or 26 and 33 and in the pipes 36 and 39 or 37 and 39 thereby equalizing each side of the diaphragm of the respective valve but if water enters the pipes 32 or 33 the weight of such water upon the diaphragm in addition to the existing pressure will disturb the balance and open the valve, thus allowing live steam to flow to the tank. The live steam then equalizes the valve under the raised pressure but the valve remains open as long as the pressure of water continues.

The normal pressure of steam in the system to which this device is connected carries

- the condensation to the valve 12. If the tank 2 is under live steam pressure ejecting, the check 9 will be closed, consequently the return steam pressure will not be sufficient to force the condensation in that direction so it will flow freely to the other tank passing through the intermediate check valve 8. The valves 27 and 28 at the top of the tanks 1 and 2 are the ordinary air valves which close automatically under steam temperature and when the steam to the tank has been cut off the temperature immediately drops and the pressure in the tank is first reduced by natural condensation and later by the opening of the air valve so that when the condensation is forced in by the return pressure the air in the tank is released. The water flows in until the tank fills and then flows into the pipe 32 and this pipe quickly fills and the water then flows in to the top of the diaphragm. The weight of the column of water overbalances the pressure on the diaphragm and opens the steam valve allowing live steam to enter the tank at the top. This immediately forces the water downwardly from the tank through the outflow check valve 19 to the feed pipe leading to the boiler. As the pressure on the top of the tank is equalized with boiler pressure the water in both the tank and the static column 32 will flow quickly to the lower level and as the static pressure on the diaphragm 31 holding the valve 29 open reduces the balance is restored and the valve is closed by the spring 38, thus relieving the tank from the boiler pressure.
- The valve 12 normally allows free inflow to the tank 1 and when said tank 1 is under high pressure, pressure through the pipe 17 opens the valve 12 allowing the condensation pressure to flow to the tank 2 as the tank 1 will be cut off by the closing of the check 8 and when the pressure on the tank 1 is released following the discharge of the water therefrom the valve 12 is automatically closed by its internal spring, thus directing the water again to the tank 1.
- From this description it will be readily understood that there will be no interruption to the flow of the condensation, that is to say, it will flow continuously to the valve 12 and will according to the setting of that valve be directed to either one or other of the tanks. Immediately either of the tanks is filled the live pressure is automatically directed to the top thereof and instantaneous discharge follows but while this discharge is occurring the other tank may receive.
- The gate valves may be manipulated to regulate the flow so that the intake and discharge will operate with substantially uniform speed so that there will be continuous movement of the water and steam.
- The working parts in a structure such as described are limited entirely to the auto-
- matic valves, consequently the amount of working mechanism to get out of order is reduced to the minimum. Such a device completely obviates the mechanical handling of a large weight of water as is required in certain traps now largely in use.
- This system has been described as applied to a steam boiler but it will be readily understood that it may be applied to any system utilizing a liquid and a gas for effecting an automatic transfer of the condensate to the source.
- What I claim as my invention is:
1. In a means for collecting and returning condensation in steam systems, the combination with the boiler and the condensation return, of a receiving tank connected at the top to the boiler steam pressure, a pipe leading to said tank from the return, a pipe leading from said tank to the boiler, a steam balanced piston valve in the steam line to the tank and spring operated to close and arranged below said tank, and a hydrostatic column leading from the upper end of the tank to said balanced valve and adapted to throw said valve off balance to direct live steam into the top of the tank and effect the discharge of the water therein to the boiler. 80
  2. In a means for collecting and returning condensation in steam systems, the combination with the boiler and the condensation return, of a receiving tank connected at the top to the boiler steam pressure, a pipe leading to said tank from the return, a pipe leading from said tank to the boiler, a steam balanced piston valve in the steam line to the tank arranged below said tank, and a hydrostatic column leading from the upper end of the tank to said balanced valve and adapted to throw said valve off balance to direct live steam into the top of the tank and effect the discharge of the water therein to the boiler. 90
  3. In a means for collecting and returning condensation in steam systems, the combination with the boiler and the condensation return, of a receiving tank connected at the top to the boiler steam pressure, a pipe leading to said tank from the return, a check valve in said pipe, a pipe leading from said tank to the boiler, a check valve in said pipe, a steam balanced piston valve in the steam line to the tank arranged below said tank, and a hydrostatic column leading from the upper end of the tank adapted to throw said valve off balance to direct live steam into the top of the tank and effect the discharge of the water therein to the boiler. 100
  4. In a means for collecting and returning condensation in steam systems, the combination with the boiler and the condensation return, of a receiving tank connected at the top to the boiler steam pressure, a pipe leading to said tank from the return, a check valve in said pipe, a pipe leading from said tank to the boiler, a check valve in said pipe, a balanced piston valve in the steam line to the tank having a diaphragm to operate same, said valve being arranged below the tank, branch steam pipes connected to each side of the diaphragm of said balanced valve, a hydrostatic column connected with the tank, and a branch from said column connected at one side of the diaphragm to overbalance the valve and operate the piston to open the steam line to the tank. 110
  5. In a means for collecting and returning condensation in steam systems, the combination with the boiler and the condensation return, of a receiving tank connected at the top to the boiler steam pressure, a pipe leading to said tank from the return, a check valve in said pipe, a pipe leading from said tank to the boiler, a check valve in said pipe, a balanced piston valve in the steam line to the tank having a diaphragm to operate same, said valve being arranged below the tank, branch steam pipes connected to each side of the diaphragm of said balanced valve, a hydrostatic column connected with the tank, and a branch from said column connected at one side of the diaphragm to overbalance the valve and operate the piston to open the steam line to the tank. 120
  6. In a means for collecting and returning condensation in steam systems, the combination with the boiler and the condensation return, of a receiving tank connected at the top to the boiler steam pressure, a pipe leading to said tank from the return, a check valve in said pipe, a pipe leading from said tank to the boiler, a check valve in said pipe, a balanced piston valve in the steam line to the tank having a diaphragm to operate same, said valve being arranged below the tank, branch steam pipes connected to each side of the diaphragm of said balanced valve, a hydrostatic column connected with the tank, and a branch from said column connected at one side of the diaphragm to overbalance the valve and operate the piston to open the steam line to the tank. 125
  7. In a means for collecting and returning condensation in steam systems, the combination with the boiler and the condensation return, of a receiving tank connected at the top to the boiler steam pressure, a pipe leading to said tank from the return, a check valve in said pipe, a pipe leading from said tank to the boiler, a check valve in said pipe, a balanced piston valve in the steam line to the tank having a diaphragm to operate same, said valve being arranged below the tank, branch steam pipes connected to each side of the diaphragm of said balanced valve, a hydrostatic column connected with the tank, and a branch from said column connected at one side of the diaphragm to overbalance the valve and operate the piston to open the steam line to the tank. 130

- 5 combination with the boiler, of a pair of receiving tanks, steam pipes leading from the boiler steam pressure to the tops of said tanks, balanced valves in said steam pipes, hydrostatic means for controlling said steam pipes regulated by the water in the tanks, a return from the steam system leading to the bottom of said tanks, a steam operated valve control arranged in said return adapted to direct the flow of condensation to either tank, said control being actuated through the opening of the valve controlling the steam supply to one of the tanks, and feed pipes leading from said tanks to the boiler.
- 10 5. In a means for collecting and returning condensation in steam systems, the combination with the boiler, of a pair of receiving tanks, steam pipes leading from the boiler to the tops of said tanks, balanced valves in said steam pipes, hydrostatic means for controlling said steam pipes regulated by the water in the tanks, a return from the steam system leading to the bottom of said tanks, a three-way valve in said return
- 15 adapted to control the flow of condensation to either of said tanks, a diaphragm operating said valve, a steam pipe connected with said diaphragm and the top of one of the tanks, and feed pipes leading from said tanks to the boiler.
- 20 6. In a means for collecting and returning condensation in steam systems, the combination with the boiler, of a pair of receiving tanks, steam pipes leading from the boiler to the tops of said tanks, balanced valves in said steam pipes, hydrostatic means for controlling said steam pipes regulated by the water in the tanks, a return from the steam system leading to the bottom of said tanks, check valves in said return allowing inflow and preventing back flow from each tank, a steam controlled three-way valve arranged between said check valves, means connecting said steam controlled valve with the top of one of said tanks, feed pipes leading from the bottoms of said tanks to the boiler, and check valves in said feed pipes opening toward the boiler.
